UNITED STATES PATENT OFFICE.

GEORGE F. ATWOOD, OF ORANGE, NEW JERSEY, ASSIGNOR OF ONE-HALF
TO FREDERICK M. HOYT, OF STAMFORD, CONNECTICUT.

MEAN-PRESSURE INDICATOR OR POWER-GAGE.

SPECIFICATION forming part of Letters Patent No. 607,819, dated July 26, 1898.

Application filed March 9, 1897. Serial No. 626,595. (No model.)

To all whom it may concern:

Be it known that I, GEORGE F. ATWOOD, a citizen of the United States, residing at Orange, in the county of Essex and State of New Jersey, have made a new and useful Invention in the Nature of a Mean-Pressure Indicator or Power-Gage, of which the following is a specification.

My invention is designed to give continuous measurements by visual indications of the amount of energy given to prime movers—such as steam, gas, air, and water motors—and in such manner that the indications will be of a "dead-beat" nature—that is to say, will give indications of varying loads put upon the prime mover without sudden or violent fluctuations.

To this end my invention consists in a novel apparatus for accomplishing this result, and the especial points of novelty thereof will be particularly pointed out in the claims at the end of the following specification, reference being had to the accompanying drawings for a full understanding of the invention, in which—

Figure 1 is a vertical sectional view of the entire apparatus, taken on the lines 1 1, Fig. 3, and 1 1, Fig. 4, and as seen looking at those figures in the direction of the arrows from the bottom toward the top of the drawings. Fig. 2 is a plan view as seen looking at Fig. 1 from the bottom toward the top of the drawings, part of the protecting or inclosing casting of the propelling turbine or motor being broken away for the better illustration of the interior structure thereof. Fig. 3 is a plan view of the instrument as seen looking at Fig. 1 from the top toward the bottom of the drawings, said figure illustrating the dial and the dial or indicating hand in zero position in full lines and in operative position in dotted lines, together with a view of the retarding-spring attached to the shaft for retarding the forward movement of the dial-hand. Fig. 4 is a horizontal sectional view taken on the broken sectional line 4 4, Fig. 1, and as seen looking in the direction of the arrows upon that figure from the top toward the bottom of the drawings. Fig. 5 is a sectional view, taken through the body of the turbine or pro-

pelling-motor and its adjacent parts, illustrating the manner of connecting the steam-pipes to the jet-pipes through which the steam flows to the motor, the propelling-fan connected thereto being shown in elevational view. Fig. 6 is a sectional view of the cylinder of a well-known form of steam-engine, illustrating the manner of connecting my steam-dynamometer thereto and its mode of operation in connection therewith. 55

Prior to my invention it was customary in obtaining the horse-power of steam-engines or analogous prime movers to utilize a steam-indicator the motive part of which was actuated by the steam as it entered the cylinder 60 at one end thereof and caused to trace a diagram upon a card during one or two strokes of the engine or motive device. This diagram was then used as the basis of a computation of the amount of energy given to the piston 65 during the particular interval occupied in its construction. The calculations were usually made by tracing the diagram or card by a planimeter in order to obtain the area thereof, and then by a well-known formula the 70 mean effective pressure and total energy were calculated. This diagram or "card," as it is termed, is always traced upon a reduced scale, and it is obvious, therefore, that any error in the measurement of its area or average 75 height which represents the mean pressure will be multiplied in a ratio corresponding to the reduction of the scale upon which the card is constructed. It is well known, furthermore, that these computations involve 80 considerable time and are at best only momentary indications of the actual energy used. It is very desirable, therefore, to devise an instrument which will at all times indicate upon visual inspection the actual energy 85 given to the piston without the necessity of performing laborious calculations, and it was with this end in view that the present invention was conceived and devised.

The well-known formula for calculating 90 the energy of an engine contemplates the multiplying the area of the piston-head in square inches by the mean effective pressure and the multiplication of this product by the distance traveled in feet per minute, which 95 100

total product is divided by thirty-three thousand foot-pounds. The area of the piston-head and thirty-three thousand foot-pounds being constant the quantities to be measured 5 are therefore the mean effective pressure and the velocity in feet per minute. The latter is easily obtained by measuring the revolutions per minute of the shaft of the engine and multiplying the same by twice the length 10 of the stroke in feet; but, as above explained, the measurement of the mean effective pressure involves the described method of tracing a diagram with an indicator.

In all self-governing engines the speed is 15 practically constant, and an instrument that will measure and indicate the mean effective pressure can be calibrated so as to read in units of horse-power, inasmuch as the quantities are constant, with the exception of that 20 which is to be measured, and it will vary in proportion to the total energy or horse-power. The above holds true, however, only when the conditions are as ordinarily found with existing self-governed steam-engines and a 25 properly-constructed indicating instrument. My invention comprehends such an instrument and is adapted to be attached to either or both ends of the cylinder of well-known forms of steam-engines, and in practice I use 30 a small turbine or rotary motor actuated by one or more jets of steam or water directed through a jet pipe or nozzle and impinging upon the blades or buckets thereof at its periphery or sides. The shaft of this turbine 35 or rotary motor is connected mechanically to a dynamometer which will balance or measure the force given by the jet or jets of steam or water, and the scale of the dynamometer may be either graduated arbitrarily and the reading multiplied by a constant, or it may be 40 calibrated empirically from actual tests, thus indicating the desired units of energy—such, for instance, as mean effective pressure or horse-power.

45 Referring now to the drawings in detail, in all of which like letters of reference represent like parts wherever used, A represents a metallic cylindrical inclosing casing secured by screws *a a a* to a cylindrical motor-chamber B', which in turn is secured to a base or support B by screws *n n n*, extending upward into a rim V, said parts when united together constituting a steam-tight chamber for a 50 rotary turbine or motor T of disk form, having its undersurface provided with radial grooves or buckets *g g* and surrounded in turn by a metallic band or rim *r*, said motor being secured by a drum or shaft S', provided with ball-bearings *b b* at its opposite ends and 55 adapted to rotate upon said bearings around a shaft S', supported by a stationary shaft S, extending downward in a hub or extension R' in the bottom of the part B.

60 *t t'* are steam or water jet pipes secured in 65 the upper ends of the steam-tight collars K K' and located at such angles that the steam

emitted therefrom will give to the rotary turbine or motor T rotation in the direction of the arrow, Fig. 2.

F is a rotary fan having two or more blades 70 or vanes secured to the hollow shaft S² and adapted to rotate therewith in a chamber above the steam-chamber B'. F' is a similar rotary fan carried by a shaft s², provided with a delicate jewel-bearing *j* in the upper end of 75 the shaft S' and a second delicate jewel-bearing *j'* in a set-screw *s'*, supported by the free end of an arm E², secured by screws *e e* to the top of an instrument and above a dial-plate D, calibrated, as shown, and sustained by posts 80 or pillars *p p*.

G is a glass cover inclosing the dial D and dial-hand H, said cover being secured to the inclosing casing A by a ring or rim R and screws *o o*. 85

D' is a Foucault disk, of copper or other diamagnetic material, sustained by the shaft s² and adapted to rotate between the poles of a number of permanent magnets M M M, its function being to steady the dial-hand H from 90 violent fluctuations upon sudden changes of speed of the turbine or motor T and give to it a dead-beat action.

s is a delicate spiral retractile spring secured at one end to the shaft s² and at the 95 other to the body or frame of the instrument.

P and P' are pipes for admitting a motive agent, such as steam or water, to the jet-pipes *t t'*, said pipes being secured at opposite ends of the cylinder, as shown in Fig. 6, and connected to the steam-tight collars K K' by screw-threaded collars Q, having frictional bearing upon rims or beads *v v*, *m m* being steam-tight packing-rings of well-known form. The steam-tight collars K K' are secured to the base B of the steam-chamber B' 105 by set-nuts N N', clamping said collars thereto through the agency of beads or rims L L.

E is an exhaust-pipe for permitting of the exhaust of the motive agent—such as steam, 110 air, gas, or water—after it has passed through the instrument, said exhaust-pipe being secured to the steam-chamber B' by screw-threads, as clearly indicated at E⁴ in Fig. 2, and connected directly with the main exhaust-pipe of the engine proper, so that the conditions of exhaust for the instrument are similar to those of the engine. 115

E' is an extension or lug on the lower part 120 of the base B of the steam-chamber B', and W is a screw-bolt provided with a milled head and a set-nut J, its function being to bear upon an arm Z, attached to each of the steam-collars K or K' and in such manner that the angular location of the steam-jet pipes *t* and *t'* may be varied at will, thereby affording 125 means for varying the speed of the rotary turbine or motor and adjusting the instrument to the engine with which it is to be permanently used.

130 My invention depends for its operation upon the fact that an additional path or out-

let for the steam or motive agent is provided from the cylinder of the engine or prime mover through the motor of a mean-pressure indicator to the exhaust of the prime mover 5 or its equivalent, so that I thereby utilize or absorb a portion of the steam or motive agent which is given to the cylinder of the prime mover or engine to drive such a motor having a sufficient moment of inertia to enable 10 it to run at a practically constant velocity for successive impulses of equal values in pressures and duration, which motor in turn drives indicating mechanism adapted to indicate directly in established units the power 15 or pressure utilized to drive the prime mover or engine, and this is accomplished by causing the steam which successively enters the cylinder at opposite ends behind the piston to continuously drive a rotary motor having 20 a definite moment of inertia and adapted to perform a definite amount of work proportional to the work performed by the prime mover or engine the power of which it is desired to ascertain, and in the application of 25 this generic principle of measuring a definite proportion of power used and giving a direct visual indication of the same lies the essence of my invention.

In constructing my improved apparatus it 30 will be understood that the dials are calibrated for engines of known horse-power and the spiral retractile springs *s* therefor are of a known retractile capacity, so that when an apparatus is constructed for a given engine of, 35 say, one hundred horse-power and properly adjusted it will give correct readings during the usage of the same for all intermediate powers. Although I preferably connect my indicator to both ends of the cylinder by 40 steam-pipes *P P'*, so as to give the same impulsive effect upon the indicating-motor as is had upon the piston proper of the engine, it is obvious that it might be connected at either end thereof at will; but by connecting to 45 both ends I obtain more accurate results.

My improved apparatus for indicating horse-power is operated as follows: The dynamometer is connected by steam-pipes *P P'* to the opposite ends of the cylinder *C*, as shown 50 in Fig. 6, and the engine set in operation in the usual way, a well-known form of valve mechanism therefor being shown at the lower part of that figure. As the steam is admitted to one end of the cylinder—say the right—a 55 definite proportion of it passes through the steam-pipe *P'* and collar *K'* to the jet-pipe *t'*, and in passing therefrom acts in a well-known manner upon the grooves or buckets *g* of the turbine or rotary motor *T*, tending to set the 60 same in motion. When the piston reaches its extreme stroke on the left, steam now enters through the pipe *P* and collar *K* and jet-pipe *t*, acting in the same manner upon the turbine *T*, the exhaust-steam passing out of the 65 chamber *B'* by the exhaust-pipe *E*. This successive impulsive action sets the turbine

or rotary motor in operation and imparts thereby continuous rotary movement to the propelling-fan *F* in such manner as to set in circulation in a given direction the volume of 70 air within the chamber, which in turn acts upon the blades of the fan *F'*, thus causing it to tend to rotate against the stress of the spiral spring *s* and dampening effect of the magnets *M* upon the diamagnetic Foucault 75 disk *D'*. As the engine speeds up the dial-hand *H* continues to move to the right until the actual energy absorbed is indicated on the dial. Any sudden increase upon the demands of the engine is of course followed by a corresponding inflow of steam into the cylinder, and consequently by a proportional flow of 80 such steam to the rotary turbine or motor *T*, thus ultimately indicating directly upon the dial the proportionate change. 85

It will be apparent that the Foucault disk *D'*, the retractile spring *s*, and fan *F'* are of such nature as to act when in operation with a retarding action upon the speed of the propelling-fan *F*, and consequently the motor 90 will have a velocity bearing a certain measure or proportion to the mean effective pressure applied. I find upon actual use of the invention that it is in effect a dead-beat instrument—that is to say, any variation in the actual energy absorbed by the engine is indicated by a gradual increasing or decreasing movement of the dial-hand *H* either to the right or the left, dependent upon an increase or decrease of the energy absorbed, as the case 95 may be.

Although I have disclosed herein a special form of apparatus for indicating directly the actual energy of an engine, I do not limit myself to the particular mechanism shown and 105 described, as I believe that I am broadly entitled to claim a mean-pressure indicator propelled by a definite proportion of the steam used which will indicate directly to the user any variation of pressure in established units, 110 and my claims are generic as to this feature. I also desire it understood that my invention is applicable alike to all classes of engines, whether operated by water, steam, air, gas, or such vapors as are ordinarily used expansively 115 in the art of generating motive power. In short, I believe my invention to be of such scope as to entitle me to claim generically a mean-pressure indicator which gives direct readings of the effective pressure given to the 120 engine to which it is attached.

Having thus described my invention, what I claim, and desire to secure by Letters Patent of the United States, is—

1. A mean-pressure indicator or power-gage 125 meter for steam, or analogous engines, consisting of a continuously-driven motor actuated directly by a part of the steam which drives the engine and having sufficient momentum to make its velocity substantially 130 constant for successive impulse effects of the steam when of equal value, and an indicator

driven by the motor and adapted to give visual indications of a unitary nature, substantially as described.

2. A mean-pressure indicator or power-gage consisting of a turbine motor having sufficient momentum to continue its movement during the interval between successive impulses of the moving agent, said motor being attached to a rotary fan, in combination with a second fan adapted to be propelled by the first-named fan and an indicating-hand carried by a shaft which sustains the second fan; means as a retractile spring for retarding or opposing the forward movement of said fan, together with a dial calibrated to read units of measurement, substantially as described.

15 3. A mean-pressure indicator or power-gage meter for steam or analogous engines consisting of a rotary motor actuated directly by a part of the motive agent which drives the engine and having a sufficient moment of inertia to render its velocity a measure of the mean pressure of the successive impulses of such motive agent, in combination with an indicator driven by the motor and adapted to give visual indications of a unitary nature, such as horse-power, substantially as described.

20 4. A mean-pressure indicator or power-gage meter consisting of a turbine motor having a sufficient moment of inertia to continue its movement in the same direction between successive impulses of the motive agent, such as steam, in combination with one or more jet-pipes adapted to convey a part of the motive agent directly from the cylinder of the engine to and through the turbine motor at the same time that it is applied to the piston-head of the engine together with means for indicat-

ing definite units of energy attached directly to the movable part of said turbine motor, substantially as described.

25 5. A mean-pressure indicator or power-gage consisting of a movable motive device in the nature of a rotary turbine, said motive device having sufficient moment of inertia to continue its movement during successive applications of the motive agent, such as steam; one or more jet-pipes operatively connected with the engine the horse-power of which it is desired to ascertain, said jet-pipe or jet-pipes being so connected to the engine as to receive the steam therefrom at the same time that it is utilized by the engine, in combination with indicating mechanism driven by said rotary turbine, and opposing means in the nature of a retractile spring together with steadyng means, all of said parts acting substantially as and for the purpose described.

30 6. A mean-pressure indicator or power-gage meter for steam or analogous prime movers or engines, consisting of a continuously-driven turbine constructed to have a sufficient moment of inertia to continue its movement during successive impulses and provided with one or more jet-pipes adapted to deliver steam upon the buckets of the motor; means for varying the angular location of said jet-pipes so as to adjust the instrument to the prime mover with which it is to be moved, in combination with an indicator driven by the motor, substantially as described.

In testimony whereof I have hereunto subscribed my name this 8th day of March, 1897.

GEORGE F. ATWOOD.
